CLAIM

We claim the ornamental design for a mobile accessory, as shown and described.

DESCRIPTION

FIG. 1 is a side perspective view of the mobile accessory; FIG. 2 is a front view of FIG. 1; FIG. 3 is a rear view of FIG. 1; FIG. 4 is a left side view of FIG. 1; FIG. 5 is a right side view of FIG. 1; FIG. 6 is a top view of FIG. 1; and, FIG. 7 is a bottom view of FIG. 1.

The broken lines in the drawings depict parts of the mobile accessory that form no part of the claimed design.
